COMBINATION RECIPROCATING AND ROTATING TOOL

Lawrence Lynch, Los Angeles, Calif.

Application June 24, 1948, Serial No. 34,907

11 Claims. (CL. 74—57)

1

This invention relates to a power driven hand tool which is adapted for various purposes such as drilling, filing and sawing, or for peening.

It is the object of my invention to provide a tool of the character referred to which may quickly and conveniently be adjusted to suit the various operations for which it is adapted. It is a further object of the invention to provide a tool of this class which may be readjusted by simple manual operations and without having to resort to use of mechanical means for effecting such adjustments.

These and other objects of the invention will be better understood from the following detail description and reference is invited to the accompanying drawings in which a preferred form of the invention is illustrated.

In the drawings:

Fig. 1 is a side view partly in section of a device embodying the invention;

Fig. 2 is a view of the main portion of the device taken at right angles to Fig. 1;

Fig. 3 is a cross-sectional end view taken substantially on line 3—3 of Fig. 1; and

Figs. 4 and 5 illustrate elements of the device, the importance of which is hereinafter fully explained.

As indicated in the drawings, the tool of my invention includes generally a cylindrical body portion 1, within which a driving member 2 is rotatably fitted and a stem 3 extends axially through this member and the body of the tool for rotating or reciprocating movement thereon, according to the condition of adjustment thereof, the rear end of the driving member is shown internally threaded to receive a flexible shaft 4, such as conventionally used in tools of this type.

As shown in Fig. 1, peripheral cam grooves 5, 6 of different pitch are cut into the stem 3 of a size to receive a ball 7 which normally is held correctly positioned within one of the grooves by means which will be described presently. In addition to the cam grooves just referred to, a recess 8 is axially cut into the stem of a size to receive a second ball 9 and the latter is similarly maintained in correct position within this recess by means which will now be described.

A recess 15 is cut into the periphery of the tool body at right angles to the axis thereof of a size to receive therein a block 16, the inner surface of which is recessed fittingly to receive the ball 9, and the block is above this recess shown perforated to receive the inner end of a pawl 18. The latter is mounted for oscillating movement within a groove of the body by means of a pivot 19.

2

and it is fitted with a finger piece 20, the outer surface of which corresponds to the peripheral outline of the body. A compression spring 21 is placed within this finger piece normally to maintain the block 16 in the position indicated in Fig. 3 and this spring is conveniently maintained in position by means of a lip 22 which projects inwardly from the inner surface of the finger piece. It is seen from the foregoing brief description that the stem 3 is held against rotation by the ball 9 riding in the groove 8, but that it is free to move axially within the tool body.

As the ball 9 is maintained in position within the tool body so the ball 7 is held in position within the driving member 2 in the following manner. A recess 25 is sunk in the periphery of this member of a size to receive therein a block 26 which may be very similar to the above described block 16 and which is similarly recessed at the bottom thereof to receive the ball 7. A pawl 27 is mounted within the driving member on a pivot 28 and the inner end of this pawl engages a perforation 29 of the block 26 in a manner similar to that in which the pawl 18 engages the perforation of the block 16. The pawl is fitted with a finger piece 30 which extends in continued alignment with the pawl and substantially in axial relation to the driving member. A spring 31 urges the pawl into the position indicated in Fig. 1 to maintain the ball 7 correctly seated within the cam groove 6 of the stem.

The body portion of the tool is made with a shallow groove in the periphery thereof, within which an outer shell 32 is fitted for rotatory movement therein. It is important to note that the shell, as best indicated in Fig. 3, clears the finger piece 20 of the pawl 18 so as to leave the spring 21 free to seat the ball as required in order to maintain the ball correctly seated within the groove of the stem.

It should be clear from the foregoing brief description that rotation of the driving member is, by the ball 7 within the cam groove 6, translated into a reciprocating movement of the stem of the length required for filing or sawing operations and that the ball 9, riding within the groove 8, maintains the stem unturned during the reciprocations thereof.

As above stated, a second cam groove 5 is sunk into the periphery of the stem and this cam groove is designed to impart to the stem shorter reciprocating movement such as required for peening operations. In order to utilize this second cam groove, it becomes necessary to transfer the ball 7 from the cam groove 6 thereinto. For the pur-

pose of such transfer, it is merely required to turn the outer shell 32 on the body portion of the tool until the opening 33 of this shell reaches the position indicated in Fig. 2, wherein the finger piece 30 of the pawl 26 is shown fully exposed. While in this position, it is merely required manually to depress the finger piece, thereby to cause the ball 7 to rise out of the cam groove 6. The stem 3 is then moved axially until the pawl reaches the position to register with the cam groove 5. Pressure on the finger piece 30 may then be released whereupon the spring 31 will seat the ball in this second groove. The outer shell may then be returned to its initial position to lock the parts in the correct position, as required for the operation of the tool. For convenience in performing this adjustment, the stem may be fitted with graduations for registration with the front face of the tool body, as indicated in Fig. 1, the letters P R and S pointing to the location of these lines which indicate these positions. The two cam grooves should be sufficient for most peening and sawing operations, but additional grooves may be added if required.

It was above stated that one of the objects of the invention is to adapt the tool for drilling purposes also and such adjustment may be effected by releasing the ball 7 from the cam groove 6 of Fig. 1, in the manner above described and by pushing the stem 3 further into the tool until the ball 9, which at the same time has been elevated by depressing the finger piece 20, registers with the outer peripheral surface of the stem 3 beyond the end of the groove 8 and the ball 7 at the same time reaches the position of registration with this groove. When the outer shell now is returned to its initial closing position, it is seen that the stem is held by the ball 7 against rotation relative to the driving member, but that both are free to rotate within the tool body, as required for the purpose of performing drilling operations. A drill chuck 35 may then be mounted in position on the threaded end of the stem. The latter is also shown recessed in the end thereof to receive the shank of a file or saw and a set screw 36 is provided for the purpose of locking such tool in position therein.

When the balls 7 and 9 are carefully and tightly fitted within their sockets in their blocks 16 and 25, and when a heavy grease has been applied to the stem, as is practice with tools of this kind, it is found that the ball will be held firmly within its socket when it is raised out of its groove. Should it, however, be found that due to improper lubrication or otherwise, a danger would be present of the ball not remaining within the block when elevated from its groove, it is possible to provide means for tying the ball to the pawl which elevates the block. Such means is, in Fig. 5, shown to comprise a stud 37 which projects downward from the block 26 and extends through a perforation of the ball. This perforation should be slightly countersunk at the bottom and the end of the stud slightly spread so as to lock the ball in position thereon. When so mounted, it is found that the ball will be positively elevated and yet will be free to rotate on the stud, as required during the operation of the tool. It is to be understood that a similar stud 38 is provided to lock the ball 9 in position within its socket in the block 16, as indicated in Fig. 4.

The body of the tool is shown made in three parts 10, 11 and 12, the adjoining ends of which are provided with screw threads for the purpose of drawing the three parts together after the

outer shell 32 has been placed in position on the central member 11. It is also to be noted that suitable roller or pin bearings 13, 14 may be placed between the driving member and the body member 11 for the purpose of eliminating friction between these parts and it may be well, in addition, to provide a thrust bearing 23 further to eliminate friction between these parts. Other modifications may be embodied within the scope of the claims hereto appended.

I claim:

1. A tool reciprocating device comprising, a casing, a cylindrical stem mounted for axial movement within the casing but held against rotation therein, cam grooves in said stem of different pitch, a ball for engagement with any one of said cam grooves, and a support for said ball, said support being manually operable to withdraw the ball from its groove, the stem being axially movable to bring another groove into registration with the ball.

2. A tool reciprocating device comprising, a casing, a cylindrical stem mounted for axial movement within the casing but held against rotation therein, cam grooves in said stem of different pitch, a ball for engagement with any one of said cam grooves, a ball support, and a lever engaging said support, the lever being manually movable to raise the support to withdraw the ball from its groove, the stem being axially movable to bring another groove into registration with the ball.

3. A tool reciprocating device comprising, a casing, a cylindrical stem mounted for axial movement within the casing but held against rotation therein, cam grooves in said stem of different pitch, a ball for engagement with any one of said cam grooves, a ball support, a lever engaging said support, and a spring urging movement of the lever to press the ball into the groove, the lever being manually movable against the tension of said spring to raise the support to draw the ball from its groove, the stem being axially movable to bring another groove into registration with the ball.

4. A tool reciprocating device comprising, a casing, a cylindrical stem mounted for axial movement within the casing but held against rotation therein, cam grooves in said stem of different pitch, a ball for engagement with any one of said cam grooves, a support for said ball, and a spring urging said support inward to press the ball into the groove, said support being manually operable against the tension of said spring to withdraw the ball from its groove, the stem being axially movable to bring another groove into registration with the ball.

5. A tool reciprocating device comprising, a casing, a cylindrical stem mounted for axial movement within the casing but held against rotation therein, cam grooves in said stem of different pitch, a ball for engagement with any one of said cam grooves, a support for said ball, said support being manually operable to withdraw the ball from its groove, the stem being axially movable to bring another groove into registration with the ball, and means for anchoring the ball in the support for rotation therein.

6. A tool reciprocating device comprising, a casing, a cylindrical stem mounted for axial movement within the casing but held against rotation therein, cam grooves in said stem of different pitch, a ball for engagement with any one of said cam grooves, a ball support, a lever engaging said support, the lever being manually movable to raise the support to withdraw the ball from its groove,

the stem being axially movable to bring another groove into registration with the ball, and means for anchoring the ball for rotatory movement within the support.

7. A tool reciprocating device comprising a cylindrical casing, a cylindrical stem axially movable within said casing, cam grooves in said stem of different pitch, a ball, a support for said ball, a spring urging movement of said support to seat said ball in one of said grooves, the support being manually movable against the tension of said spring to withdraw the ball from its groove, the stem being axially movable to bring another groove into registration with the ball, an axially directed groove in the stem, and a ball in said groove preventing rotation of the stem.

8. A tool reciprocating device comprising, a cylindrical casing, a cylindrical stem mounted for axial movement within the casing but held against rotation therein, cam grooves in said stem of different pitch, a ball for engagement with any one of said cam grooves, a support for said ball, and a cylindrical sleeve rotatably encompassing the casing and having an opening for registration with said support, the support being manually operable to withdraw the ball from its groove when the sleeve opening is brought into registration therewith, the stem being axially movable to bring another groove into registration with the ball.

9. A tool reciprocating device comprising, a casing, a cylindrical stem mounted for axial movement within the casing but held against rotation therein, cam grooves in said stem of different pitch, a ball for engagement with any one of said cam grooves, a ball support, a lever engaging said support, and a cylindrical sleeve rotatably encompassing the casing and having an opening for registration with said lever, the lever being manually movable to raise the support to withdraw the ball from its groove when the sleeve opening is

5

brought into registration therewith, the stem being axially movable to bring another groove into registration with the ball.

10. A tool rotating and reciprocating device comprising, a cylindrical casing, a cylindrical stem mounted for axial movement within the casing, a cam groove in said stem, a ball rotatably seatable in said groove, an axially directed groove in the stem, a ball seated therein, supports for said balls, and a cylindrical sleeve encompassing the casing and having an opening therein for registration with said supports, the latter being manually operable to lift the balls from their grooves, the stem being axially movable to bring the axial groove into registration with said cam groove ball and the second ball out of said axial groove.

11. A tool rotating and reciprocating device comprising, a cylindrical casing, a cylindrical stem mounted for axial movement within the casing, cam grooves in said stem of different pitch, a ball rotatably seatable in any one of said grooves, an axially directed groove in the stem, a ball seated therein, supports for said balls, and a cylindrical sleeve encompassing the casing and having an opening therein for registration with said supports, the latter being manually operable to lift the balls from their grooves, the stem being axially movable to bring the axial groove into registration with said cam groove ball and the second ball out of said axial groove.
